UNITED STATES PATENT OFFICE.

ROBERT D. GRAY, OF RIDGEWOOD, NEW JERSEY.

REFLECTOR.

1,133,955.

Specification of Letters Patent. Patented Mar. 30, 1915.

Application filed March 21, 1914. Serial No. 826,368.

To all whom it may concern:

Be it known that I, ROBERT D. GRAY, a citizen of the United States, residing at Ridgewood, in the county of Bergen and State of New Jersey, have invented new and useful Improvements in Reflectors, of which the following is a specification.

The present invention relates to reflectors for reflecting all the light issuing from an illuminant, and it is constructed on the principle that the normal at any point of an ellipse bisects the angle formed by the focal radii.

Heretofore, it has been proposed to use a parabolic reflector for reflecting all the light issuing from an illuminant. With this type of reflector the reflected rays of light issuing from the illuminant in the focus of the reflector and falling onto the reflecting surface, are reflected in lines parallel to the axis of the reflector. This direction of extension on the part of the reflected rays with respect to the axis of the reflector, is due to the fact that the normal to a parabola at any point, bisects the angle between the focal radius and the line drawn through the point parallel to the axis, or in other words, the normal to the point of incidence of any ray issuing from the illuminant and falling onto the reflecting surface, makes equal angles with the incident and reflected rays. As a consequence of this, it will be obvious, that maximum efficiency of a parabolic reflector can be had only in instances where the surface onto which it is desired to direct the reflected beam, is as large or larger than the cross sectional area of the largest part of the reflector. If the said surface be smaller than the open end of the reflector, then the effect of the light rays immediately beyond the said surface is not had or the same. Therefore, a parabolic reflector is undesirable in instances where it is desired to obtain the maximum efficiency of a relatively large reflector on a relatively small surface. Now by virtue of that property of an ellipse as hereinbefore stated, it is evident that with an elliptical reflector a ray of light issuing from an illuminant in one of the foci of an elliptical reflector and falling onto the reflector, is reflected in a line oblique to the axis of the reflector and onto the other of the foci. A normal to the point of incidence to this ray will be found to bisect the angle formed by the incident and reflected rays, as does a normal at any point of an ellipse

bisect the angle formed by the focal radii as hereinbefore stated.

Having thus stated the properties upon which depend the uses of parabolic reflectors and elliptical reflectors, and pointed out wherein each type differs from the other in point of direction of extension of the reflected rays, I now come to the present invention which has for its general object the adapting of the surface of a reflector to direct the rays of light reflected thereby in a direction oblique to the axis of the reflector and onto a point in axial alinement with the illuminant or source of light. And to that end the present invention resides in providing an elliptical reflector and arranging an illuminant in the focus of this reflector so that the reflected rays will be directed in a direction obliquely to the axis of the reflector and onto a point in alinement with the illuminant or onto the other focus of the imaginary ellipse of which the reflector forms a part.

Other objects will appear and be better understood from that embodiment of my invention of which the following is a specification, reference being had to the accompanying drawings forming part hereof, in which:

Figure 1 is a perspective of the invention. Fig. 2 is a diagrammatic view showing the principle of the invention. Fig. 3 is a side elevation showing the invention in use.

In that embodiment of my invention shown in the drawings the reflector is indicated generally by *a* and comprises a casing *b*, a reflecting surface *c* and an illuminant *d*.

The casing may be of any material found suitable for the purpose, as metal. In the embodiment shown the casing is made up of a plurality of tapered circular portions 5 and 6 arranged end to end and permanently joined together in any suitable manner, such as by rolling the meeting edge of one around the corresponding part of the other, as indicated by 7.

The reflecting surface *c* on the interior of the casing *b*, may be of any approved construction and in section longitudinally of the casing this surface may be semi-elliptical in contour or may be constructed in concentric sections each of which is tangent to an ellipse. For ordinary purposes the reflecting surface may be continuous as in the case of the ordinary parabolic reflector, but for a certain class of work which will be

hereinafter described, the reflecting surface used in connection with that work, will be plane and formed of concentric sections and this for the purpose of obtaining reflected rays of equal focal length, which, as is well-known, is impossible to obtain in the curvilinear type of reflector, on account of the aberrations invariably present there.

As shown the concentric rows 8-8 which go to make up the reflecting surface, consist each of a plurality of plane mirrors whose side edges abut and are formed so as to fit nicely one against the other, whereby to avoid the presence of ordinary perceptible seams or joints. The mirrors in one row are preferably arranged so as to break joint with those of an adjacent row, but if desired corresponding mirrors in the several rows may be made to align. In either event, however, succeeding mirrors in successive rows will extend tangentially to an elliptical curve common to the several mirrors. The mirrors are secured to the casing in any approved manner, such as by an adhesive, and a clamping structure or stop 9 may be arranged at the outer end of the casing for protecting the outer edges of the outer row of mirrors. The illuminant *d* is arranged in a focus of imaginary ellipses to which the mirrors 8 are tangent. This illuminant may be of any preferred type and for purposes of illustration, I have shown it as an incandescent electric lamp, which is arranged in a suitable socket 10 formed with the casing, which socket is provided with the usual switch button 11 for controlling the flow of current to the lamp and which is adapted to receive the wires of an electric circuit.

The structure thus shown and described may be used for any of the purposes required of an ordinary reflector but it is ideally adapted for photographic enlarging work. In the drawings I have shown the reflector in use with a photographic enlarging apparatus. Such apparatus is indicated by 12 and is adapted for containing the negative 13. Here the reflector is provided with a suitable bracket 14 for securing it upright in a container 15 which is provided with a ground glass 16. The lens system in the lens barrel 17 and the lamp are arranged in axial alignment and for such distances apart as to

form the foci of an ellipse as shown in Fig. 2 of the drawings. Consequently with this construction, the reflected rays of light are directed into the lens, as shown in the said Fig. 2.

Inasmuch as maximum efficiency on the part of a reflector of this type and when used in connection with photographic enlarging apparatus, can be had only when the maximum number of reflected rays are directed into the lens barrel, it is obvious that in order to so reflect all the light with a plane mirror such mirror should approximate in two dimensions, namely, length and width, corresponding dimensions of the flame, or as in the present instance, the incandescent filament in the electric lamp. Therefore, I preferably employ plane mirrors corresponding in surface area approximately to the area of the filament, but it must be understood that I do not intend to limit myself to this structure.

What is claimed as new is:

An apparatus for reflecting light rays so that these will converge at a point remote from the apparatus, and comprising a casing open at one end and adapted for containing an incandescent electric lamp and supporting this lamp with its axis in alignment with the point on which the reflected rays converge, and a plurality of circular rows of plane mirrors arranged on the inner surface of the said casing, the said rows being concentric and arranged one in front of the other with the adjacent ends of the mirrors in each abutting, the successive surfaces of mirrors in adjacent rows being arranged at tangents to a common semi-elliptical curve, the mirrors in successive rows progressively increasing in length from the inner end of the casing, and each of such mirrors being proportioned in two dimensions so as to correspond approximately to the corresponding dimensions of the light image to be reflected thereby.

In testimony whereof I affix my signature in presence of two witnesses.

ROBERT D. GRAY.
